UNITED STATES PATENT OFFICE.

ADOLF G. KROCKER, OF WACO, TEXAS.

ICE-BREAKING MACHINE.

1,133,863.

Specification of Letters Patent. Patented Mar. 30, 1915.

Application filed June 22, 1914. Serial No. 846,495.

To all whom it may concern:

Be it known that I, ADOLF G. KROCKER, a citizen of the United States, residing at Waco, in the county of McLennan and State of Texas, have invented a new and useful Improvement in Ice-Breaking Machines, of which the following is a specification.

This invention relates to ice breaking machines, and one of the principal objects of the invention is to provide a machine whereby cakes of ice may be broken up into pieces of the desired dimensions, in a quick and accurate manner and with a minimum amount of waste.

Another object of the invention is to provide an improved ice breaking machine including a top and bottom frame movable toward each other, and provided with rows of prongs arranged according to the size of cakes desired, means being provided whereby the frames may be moved toward each other and into engagement with a cake of ice for breaking the latter into pieces of the desired size.

A further object of the invention is to provide an improved ice breaking machine of the class described which will be extremely simple, durable, efficient in operation and inexpensive to manufacture.

With these and other objects in view which will become apparent as the description proceeds, the invention resides in the construction, combination and arrangement of parts, hereinafter more fully described, and claimed and illustrated in the accompanying drawing, in which like characters of reference indicate like parts throughout the several figures, of which—

Figure 1 represents a front elevational view of an ice breaking machine constructed according to my invention. Fig. 2 represents an end elevational view thereof. Fig. 3 represents a fragmentary horizontal sectional view taken on the plane indicated by the line 3—3 of Fig. 2, and Fig. 4 represents a vertical transverse sectional view taken on the plane indicated by the line 4—4 of Fig. 3.

Referring more particularly to the drawing, the machine includes a frame work comprising corner uprights 5 connected at their opposite ends at the front of the machine by the longitudinal upper and lower cross bars 6 and 7 respectively, and at the rear of the machine by the longitudinal upper and lower cross bars 8 and 9 respectively. The

upper ends of the uprights are further connected by end bars 10.

An ice rack which is stationary relatively to the main frame work comprises end bars 11 secured at the ends of the machine between the corner posts or uprights and in spaced relation with the ground, said end bars 11 being connected by the longitudinal bars 12 which occur in spaced relation to each other and which support the blocks 13, which blocks are secured to the bars 12 and upon which blocks cakes of ice as they come from the factory are adapted to be placed in position to be broken by the machine.

The breaker comprises an upper and lower frame A and B respectively, each of which is made in the form of a frame including longitudinal bars 14 carrying at their ends blocks 15 adapted to slide in vertical grooves 16 provided in the corner uprights; said bars 14 being connected near their ends by transverse bars 17, and the bars 14 and 17 are provided with notches in their upper edges, for receiving the frame work 6 comprising a central longitudinal bar 18 and cross bars 19, said frame C being provided with sharp pointed steel or iron prongs 19^a which are disposed in rows in such relation as to determine the dimensions of the broken pieces of ice. A frame C is carried by each of the frames A and B and the frames are provided with rows of prongs arranged similarly, said frames C being removable so that the frames A and B may be utilized for receiving prong carrying frames of various arrangements whereby the cakes of ice may be broken up into pieces of various dimensions according to the requirements in each particular case.

The frame B rests normally, or when out of operative position, upon the longitudinal bars 12 of the ice rack, the blocks 13 being arranged so that they do not interfere with the upward movement of frame B, said blocks 13 being of such a height that when the frame B is in lowered position the upper edges of the blocks are just above the upper ends of the prongs supported by frame B so that a large cake of ice may be placed upon the blocks above the prongs as will be readily understood. In order to raise frame B at will, there is provided a treadle comprising side bars 20 having a foot platform 21 connecting them at their outer ends, said bars 20 provided centrally with transverse notches whereby they may

engage over the upper rounded edge 22 of the lower front cross bar 7, whereby said bar may act as a fulcrum for the treadle, the rear ends of the bars 20 being connected 5 by suitable links 23 with the lower breaker frame B whereby when the operator steps on the platform 21 the breaker frame will be raised, thus projecting the prongs into the ice from beneath the same. The upper 10 breaker frame A is operated by means of a hand wheel 24 carrying a screw 25 swiveled at its lower end in a socket 26 carried by cross bar 27 provided on the upper breaker frame A, said screw turning through a bearing 28 carried by a cross bar 29 disposed centrally and transversely of the main frame and connected to the bars 6 and 8 respectively.

The operation of the device may be briefly 20 described as follows: The lower breaker frame B being in its lowered position, a cake of ice may be placed upon the ice rack and the hand wheel turned to bring the prongs 19^a carried by the upper breaker frame 25 down upon the top surface of the ice, the operator at the same time stepping upon the platform 21, thus raising the prongs carried by the lower breaker frame into engagement with the under surface of the ice, 30 and upon further rotation of the screw if necessary, the ice will be broken into chunks of the desired size and with a minimum of waste.

Although I have described the preferred 35 embodiment of my invention, I may desire to make such changes in the construction, combination and arrangement of parts thereof as do not depart from the spirit of the invention and the scope of the appended 40 claims.

I claim:

1. An ice breaking machine of the class described comprising a main frame, an ice rack secured to said main frame, a lower 45 breaker frame movable relatively to the ice rack, a rack removably carried by the breaker frame and having cutters, a foot treadle fulcrumed on the main frame, links connecting said treadle with the lower 50 breaker frame, an upper breaker frame disposed above the lower breaker frame and

adapted to slide relatively to the main frame, and means for operating the upper frame.

2. An ice breaking machine comprising a 55 main frame, an ice rack secured thereto, an upper and a lower breaker frame, means for slidably supporting said breaker frames relatively to the main frame, prongs carried by said upper and lower breaker frames and 60 projecting toward each other, said ice rack including blocks adapted when the lower frame is in lowered position to receive and maintain a cake of ice above the lower frame, a treadle for moving said lower 65 frame upwardly into engagement with the ice, and a hand screw for moving the upper frame downwardly into engagement with the ice.

3. In an ice breaking machine, a stationary ice rack comprising a series of spaced blocks, a lower breaker frame movable relatively to the ice rack and provided with prongs disposed between the blocks and below the upper surface thereof when the 75 lower frame is in lowered position, means for operating said lower frame for projecting the prongs above the blocks at will, and an upper breaker frame provided with prongs and movable toward the ice rack. 80

4. An ice breaking machine including a main frame, an ice rack supported thereby, said rack comprising end bars secured to the main frame, and longitudinally spaced bars supported by the end bars, blocks supported 85 by the longitudinal bars, and a breaker frame, said frame comprising end bars adapted to rest upon the longitudinal bars of the ice rack, side bars to which the end bars are connected, co-operating means between the side bars and main frame for slidably positioning the breaker frame relatively to the main frame, and a prong carrying frame removably positioned on the breaker frame, and means for raising and 90 lowering said breaker frame, said breaker frame when in lowered position being below the upper edges of said blocks.

ADOLF G. KROCKER.
